Filed July 19, 1960, Ser. No. 61,435

Term of patent 14 years

(Cl. D26—13)

Fig. 1.

Fig. 2.

FIG. 3.

FIG. 4.

FIG. 5.

FIG. 6.

FIG. 1 is a top perspective view, of an electric blanket control, embodying my new design;

FIG. 2 is a bottom perspective view;

FIG. 3 is a top plan view;

FIG. 4 is a partial sectional view, taken on the line 4—4 of FIG. 3 in the direction of the arrows, showing the adjustable portion of the blanket control;

FIG. 5 is a side elevational view, the opposite side being substantially a mirror image thereof; and

FIG. 6 is a fragmentary bottom plan view thereof, a portion broken away for convenience in illustration.

The broken line showing of legible matter is for illustrative purposes only. A portion of the drawing figures is diagonally lined to indicate transparency.

I claim:

The ornamental design for an electric blanket control or similar article, substantially as shown and described.
